UNITED STATES PATENT OFFICE

2,436,303

CIGARETTE SNUFFER

Arthur Jenni, Twain-Harte, Calif., assignor of
one-half to James C. McCandless, San Fran-
cisco, Calif.

Application October 7, 1946, Serial No. 701,660

1 Claim. (Cl. 131—256)

1

The present invention relates to extinguishing accessories and appliances for lighted cigarettes and has more particular reference to a so-called snuffer, that is a restricted receptacle-like device into which the lighted end of the cigarette is inserted, this in a manner to snuff out the fire.

Other objects have to do with an accessory of the aforementioned type which is of utmost simplicity in construction, is practical and convenient, highly efficient in accomplishing desired results, aptly fitted to fully achieve the ends sought, and economical.

Other objects, features and advantages will become more readily apparent from the following description and the accompanying illustrative drawings.

In the drawings, wherein like numerals are employed to designate like parts throughout the same:

Figure 1 is a fragmentary front elevational view of a projectible and retractable type ash receiver such as is used in present day automobiles, the same being provided with a snuffer constructed in accordance with the principles of the present invention;

Figure 2 is a vertical sectional view taken approximately upon the plane of the line 2—2 of Figure 1, looking in the direction of the arrows;

Figure 3 is a top plan view of the snuffer and attaching bracket therefor, the section being on the line 3—3 of Figure 2, looking in the direction of the arrows; and,

Figure 4 is a section on the line 4—4 of Figure 2, looking in the direction of the arrows.

Referring now to the drawings, by distinguishing reference numerals, it will be seen that the reference character A designates an instrument panel on an automobile, the same being provided with a projectible and retractable ash receiver. I find that my snuffer may be conveniently used in receivers of this type for which reason I have chosen to illustrate said invention in connection therewith.

Considered in its broadest aspect the invention comprises an open ended glass or equivalent tube 7 having a bore 8 therein, said bore being adapted to receive the lighted end and stub of a cigarette therein. The bore is of a diameter slightly greater than the external diameter of a conventional or regulation cigarette. Hence, the cigarette can

2

be dropped down into the bore and allowed to come to rest against a suitable base. In Figure 4 it will be seen that the base is a flat plate 9 forming part of a multiple pronged fixture. The fixture is denoted by the numeral 10 and comprises the plate 9 with circumferentially spaced upstanding tube embracing and clipping spring fingers 11. The bracket or fixture is suitably mounted on the receptacle B at any point and the lower end of the tube is snapped in between the plate 9 and surrounding retaining fingers 11. It follows therefore, that if a lighted cigarette stub is dropped into the bore it comes into resting contact with the base or plate 9 and by reason of the usual no-ventilation principle the cigarette is quickly snuffed out. Or, to put it otherwise, the fire on the end of the cigarette butt or stub is extinguished through these devices in an obvious manner.

20 The gist of the invention resides in the provision of an open ended glass or equivalent tube of appropriate length and diameter wherein the bore thereof is slightly greater than the external diameter of a regular marketed cigarette, said tube being used in connection either with a stationary bracket bottom, or a regular ash tray bottom for purposes of coacting therewith and defining a butt receiving and fire extinguishing and snuffing receptacle.

25 A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

30 Minor changes in shape, size, materials and rearrangement of parts may be resorted to in actual practice so long as no departure is made from the invention as claimed.

I claim:

35 In a cigarette extinguisher of the snuffer-type, an open-ended tube of fire-proof material adapted to receive and temporarily pocket the ignited end of a disposable cigarette butt, a bracket comprising a horizontal plate of a size to substantially close one end of said tube, said plate being provided with vertical marginally arranged resilient retention and gripping fingers whereby to permit 40 said tube to be snapped in place against the plate

and held by said fingers, the plate and tube then forming, in temporary combination, an ignited cigarette snuffing receptacle, said tube being withdrawable from the fingers in order to permit the extinguished butt to be dislodged into a receiver or the like.
